Patented Sept. 24, 1918.

Inventor

Robert C. Bender

By *J. C. Grinnell, Atty.*

UNITED STATES PATENT OFFICE.

ROBERT C. BENDER, OF ST. LOUIS, MISSOURI.

INVOICE-HOLDER.

1,279,971.

Specification of Letters Patent. Patented Sept. 24, 1918.

Application filed April 23, 1918. Serial No. 230,228.

To all whom it may concern:

Be it known that I, ROBERT C. BENDER, a citizen of the United States, residing at St. Louis, Missouri, have invented a certain 5 new and useful Improvement in Invoice-Holders, of which the following is a full, clear, and exact description, such as will enable others skilled in the art to which it appertains to make and use the same, reference being had to the accompanying drawings, forming part of this specification.

My invention relates to an invoice holder particularly of the general type disclosed in Patents Nos. 1,256,866 and 1,256,867 issued 15 to me February 19, 1918, the principal object of my present invention being to generally improve upon and simplify the construction of the invoice holders disclosed in said patents; further, to provide an invoice 20 holder which is relatively simple in construction and operation, which can be easily and cheaply manufactured, and further, to combine with the body of the holder, two or more spring-held retaining fingers and 25 to provide means for simultaneously releasing said retaining fingers.

With the foregoing and other objects in view, my invention consists in certain novel features of construction and arrangement of 30 parts, hereinafter more fully described and claimed, and illustrated in the accompanying drawings, in which—

Figure 1 is a front elevational view of an invoice holder of my improved construction 35 and showing an invoice sheet or card held in position by the retaining fingers on the front of said holder.

Fig. 2 is a side elevational view of the holder.

Fig. 3 is a vertical section taken approximately on the line 3—3 of Fig. 1.

Referring by numerals to the accompanying drawings which illustrate a practical embodiment of my invention, 10 designates 45 the body of the improved holder, the same being preferably formed of a rectangular section of comparatively thin sheet metal, and portions of the top edge and upper portions of the side edges are bent forwardly and inwardly to form retaining lips or flanges 11 for a removable card 12, the same being printed with suitable headings and data, which serve as a guide for the invoices placed on the holder.

Arranged for rocking movement in suitable bearings 13 which are secured to the

front face of the body 10 near the lefthand edge thereof, are short shafts 14 of wire or the like, the outer ends thereof being formed into comparatively small crank arms 15. 60 The outer portions of these crank arms are connected by a rod 16 of wire or the like, and formed therein near the center is a short outwardly projecting loop or finger 17.

The inner ends of the shafts 14 are bent 65 to form crank arms 18 and formed integral therewith and extending transversely over the central portion of the body 10 of the holder are fingers 19, the same being preferably semi-circular or oval in cross section. 70

One end of a comparatively small torsional spring 21 is secured to one end of each shaft 14, the opposite end of said spring bearing against the face of the holder 10 and the normal tendency of each spring is 75 to cause the corresponding finger 19 to bear with yielding pressure downwardly against the face of the body 10 of the holder. Thus invoice sheets or cards such as A may be placed on the face of the holder and firmly 80 held thereon by the spring-pressed fingers 19 and as said fingers are very narrow, they cover relatively small portions of the surface of the uppermost invoice sheet or card, and as a result, all of the matter printed 85 or written on said invoice sheet can be readily observed.

To elevate the retaining fingers 19 to insert or remove an invoice sheet, the finger 17 is engaged and pushed upwardly, which 90 action simultaneously rocks the shafts 14 through the crank arms 15, and consequently swings the crank arms 18 and retaining fingers 19 upwardly as shown by dotted lines in Figs. 2 and 3. With the retaining 95 fingers thus positioned, an invoice sheet can be readily inserted or removed. The rocking motion thus imparted to shafts 14 necessarily creates tension in the torsional springs 21, and this tension is effective in returning 100 the actuated parts to their normal positions when the pressure on the finger 17 is removed.

An invoice holder of my improved construction is comparatively simple, can be 105 easily and cheaply manufactured, and provides an efficient and convenient time and labor-saving device for all business houses where invoice sheets or the like are used.

It will be readily understood that minor 110 changes in the size, form and construction of the various parts of my improved invoice

holder may be made and substituted for those herein shown and described, without departing from the spirit of my invention, the scope of which is set forth in the appended claims.

I claim:

1. An invoice holder comprising a plate, a pair of rock shafts arranged for operation on said plate near the sides thereof, crank arms carried by said rock shafts, invoice retaining fingers carried by said crank arms and extending partially across the face of the plate, and means for simultaneously actuating said rock shafts.
- 10 2. An invoice holder comprising a plate, a pair of rock shafts arranged for operation on said plate near the sides thereof, crank arms carried by said rock shafts, invoice retaining fingers carried by said crank arms and extending partially across the face of the plate, springs associated with said rock shafts for normally forcing the retaining fingers with yielding pressure toward the
- 15
- 20

face of the plate, and means for simultaneously actuating said rock shafts.

3. An invoice holder comprising a plate, portions of the edges thereof being bent to form card retaining lips, spring actuated rock shafts journaled on the plate near one side thereof, crank arms carried by said rock shafts, and invoice retaining fingers carried by said crank arms and overlying the face of the plate.

4. An invoice holder comprising a plate, portions of the edges thereof being bent to form card retaining lips, spring-held rock shafts journaled on the plate near one side thereof, crank arms carried by said rock shafts, invoice retaining fingers carried by said crank arms and overlying the face of the plate, and means for simultaneously actuating said rock shafts.

In testimony whereof I hereunto affix my signature this 20th day of April, 1918.

ROBERT C. BENDER.

Copies of this patent may be obtained for five cents each, by addressing the "Commissioner of Patents, Washington, D. C."
